(57) **CLAIM**

The ornamental design for a coffee mug as shown and described.

DESCRIPTION

FIG. 1 is a top perspective view of the coffee mug showing our new design;

FIG. 2 is a left side view thereof;

FIG. 3 is a front view thereof;

FIG. 4 is a right side view thereof;

FIG. 5 is a rear view thereof;

FIG. 6 is a top view thereof;

FIG. 7 is a bottom view thereof; and,

FIG. 8 is a top perspective view thereof showing the coffee mug in an open/drinking position.

The broken lines show portions of the coffee mug that form no part of the claimed design.

1 Claim, 7 Drawing Sheets
